UNITED STATES PATENT OFFICE.

HOSEA R. TILLISON AND CHARLES W. H. BLOOD, OF BOSTON, MASSACHUSETTS, ASSIGNORS TO THE S. A. WOODS MACHINE COMPANY, OF SAME PLACE.

PLANING MACHINERY.

SPECIFICATION forming part of Letters Patent No. 596,555, dated January 4, 1898.

Application filed June 29, 1894. Serial No. 516,100. (No model.)

To all whom it may concern:

Be it known that we, HOSEA R. TILLISON and CHARLES W. H. BLOOD, of Boston, county of Suffolk, State of Massachusetts, have invented 5 an Improvement in Planing Machinery, of which the following description, in connection with the accompanying drawings, is a specification, like letters on the drawings representing like parts.

This invention in woodworking machinery has more especial reference to planing and other machines in which rotating cutters are employed, one of the principal objects of the invention being to provide simple and efficient means for clamping in adjusted position the bearing-boxes in which the cutters are journaled. In accordance with this part of our invention we provide a suitable connection, preferably a headed bolt, between the bearing-box and its support, coöoperating with which, either directly or indirectly, is a cam, rotation of which acts through said connection to clamp the bearing-box tightly in position against the support. A yielding or 15 spring cushion is preferably interposed between the bearing-box and the said cam, said cushion serving to retain the bearing-box against its support when the connection is loosened for adjustment.

Other features of our invention will be hereinafter described, and pointed out in the claims.

In the drawings, Figure 1 is a partial side elevation of a planing-machine embodying 35 our invention; Fig. 2, a vertical sectional detail taken through one of the bearing-boxes, showing one form of clamping and adjusting mechanism; Fig. 3, a cross-sectional detail on the dotted line $x-x$, Fig. 3. Fig. 4 shows 40 one manner of connecting the clamping devices at opposite sides the machine. Figs. 5 and 6 show our invention applied to side-head-spindle boxes, and Fig. 7 a side elevation looking at the parts in Fig. 2 from the 45 right to show the yoke connecting the two boxes.

In the drawings we have illustrated our invention in connection with a planing-machine of usual construction, it being understood, 50 however, that our said invention is not restricted to such machines, but that the

same is equally applicable to any machine in which it may be found useful.

Referring to the drawings, A is the bed or frame, of suitable construction to sustain the 55 working parts, most of which are herein omitted, inasmuch as they form no essential part of our invention.

B C are usual cutter and feed-roller stands erected upon the frame, it being understood 60 that like stands are erected at opposite sides the frame and that in all respects, unless otherwise specified, the construction of mechanism at both sides the machine is the same, so that a description of the mechanism at 65 one side will be sufficient to enable the invention to be clearly understood.

Referring particularly to Figs. 1 to 4, the stand B, provided at one edge with the usual inclined face b , is slotted, as at b' , to receive 70 the connection, herein shown as a bolt c , carried by the bearing or journal box d , in which is journaled the cutter-shaft e , said box being shown as connected by a usual yoke f with its companion box at the opposite side 75 of the machine. (See Fig. 7.) The connection or bolt c has its head provided with an eye, through which is passed the cam-shaft h , journaled at its upper end in a suitable bearing h' , fixed to the top of the stand B 80 and held in position against longitudinal movement in said bearing by collars $h^2 h^2$ thereon, said shaft at its upper end being squared, as at h^3 , or otherwise suitably formed to receive an operating-handle h^4 , 85 which may or may not remain in fixed position on the shaft.

Between the cam-shaft h and the back face of the stand B is shown interposed a clamping-plate m , the flat face of which cooperates 90 with the flat face h^x on the cam-shaft (see Fig. 3) to clamp the box to the stand when the shaft is rotated, as will be hereinafter described.

That end of the connection or bolt c opposite the eye-head is threaded to receive the nut c' , between which and the face of the box is preferably interposed a yielding cushion, shown as a helical spring n .

The operation of the clamping mechanism 100 is as follows, viz: With the parts in the positions shown the spring or cushion n acts

against the nut c' and presses the bearing-box tightly against the inclined face of the stand, yet not with such force as to prevent the said box being adjusted vertically on and 5 with relation to the said stand. When the boxes at the opposite sides of the machine have been adjusted, which may be done in any suitable manner, herein by means of the usual screws o , Fig. 1, rotated through miter- 10 wheels from the horizontal shaft o' , provided with a crank o^2 , it becomes necessary to clamp the said boxes in their new or adjusted positions. This is effected in our present invention by rotating the cam-shaft h through, 15 say, one-quarter of a revolution or sufficient to turn its flat face h^x away from the flat face of the interposed plate m , thereby drawing back upon and in the line of the bolt or connection c sufficiently to completely compress 20 the cushion n and clamp the box tightly against the stand.

It will be seen that the nuts, with the spring-cushion n , when fully compressed, form, in effect, an unyielding washer between the nut 25 and the box, so that proper adjustment of the nut on the connection enables the box to be rigidly and unyieldingly held against the stand. When it becomes necessary to re-adjust the box, the cam-shaft h is turned back 30 to its position, Fig. 3—i. e., with its flat face h^x in contact with the flat face of the interposed plate m —thereby loosening the connection c sufficiently to enable the box to be moved up and down the stand, as desired, 35 the eye-head of the connection sliding along the cam-shaft h as the box is adjusted, the spring-cushion n during this time pressing the box against the stand, so as to prevent dust and chips from getting between the box 40 and the stand.

Should chips get between the box and the stand, the box could not be drawn back into its proper position against the stand and would thereby draw the cutter out of alignment, but by our invention the box is always pressed against the stand to exclude dust and chips, and is, in effect, bolted to the stand in its adjusted position by means of the cam-shaft h .

50 In the construction shown no bearing is necessary at the lower end of the cam-shaft h , inasmuch as the entire strain of clamping is received by the interposed clamping-plate m , which moves vertically with the bearing-box when the latter is adjusted, and the connection c .

In practice we prefer to connect the cam-shafts at opposite sides of the machine, so that both may be operated from one side, and for 60 this purpose Fig. 4 shows the handles h^4 at opposite sides of the machine connected by a link h^5 , which enables the boxes at opposite sides of the machine to be adjusted simultaneously. Figs. 5 and 6 show this part of our 65 invention applied to bearing-boxes for side heads of spindles. Referring to said figures, P represents one of the overhanging brackets

at the feeding-out end of the machine, the two side arms being joined in usual manner by the cross-bar or yoke p , in which is formed a slot to receive the gib p' on the face of the bearing or journal box p^2 , in which is journaled in suitable manner the usual side-head spindle p^3 . The threaded bolt p^4 and fulcrum plate or washer p^6 constitute the connection 75 between the bearing-box and its support p , said bolt in the present instance having a head p^5 , between which and the interposed fulcrum-plate p^6 is arranged the spring-cushion p^7 . The fulcrum-plate p^6 rests against the support p and at its opposite end in contact with the cam-shaft p^8 , similar in shape to the cam-shaft h , Figs. 2 and 3. Rotation of the cam-shaft p^8 acts, through the fulcrum-plate p^6 , to clamp or release the connection p^4 and 80 the bearing-box p^2 . The fulcrum-plate p^6 constitutes a washer or extended head to the bolt p^4 , thus permitting the placing of the spring-cushion p^7 at the opposite end of the bolt from the construction shown in Fig. 2, the connection 85 being otherwise arranged to slide along the cam-rod, substantially the same as shown in Fig. 2, for the adjustment of the bearing-box.

In the embodiment of our invention herein 90 shown the bearing-box is connected with its support by an independent connection—viz., a threaded bolt. This connection need not, however, necessarily be independent of the bearing-box itself, for it matters not whether 100 the connection is independent of or integral with the said box so long as the operation of the cam clamps the box in position, as described.

In the embodiment of our invention shown each bearing-box is provided with a single 105 clamping device only; but it is obvious as many clamping devices may be employed as necessary to clamp any single box in proper working position.

This invention is not restricted to the particular construction or arrangement of parts herein shown, for the same may be varied without departing from the spirit and scope of the invention.

Having described one embodiment of our 115 invention and without limiting ourselves as to details, what we claim, and desire to secure by Letters Patent, is—

1. In a machine of the class described, the combination with a support, of a bearing-box 120 made adjustable thereon, a connection on and movable with said box and extending to the back of said support, a yielding cushion interposed between said bearing-box and said connection, said bearing-box being between 125 said cushion and said support, and a rotatable cam-rod on said support and along which said connection slides during adjustment of said box, rotation of said cam-rod acting through said connection to clamp the box to 130 the support, substantially as described.

2. In a machine of the class described, the combination with a support, of a bearing-box made adjustable thereon, a bolt connection

passed through the said box and provided with an eye beyond said support, a rotatable cam-rod passed through said eye arranged on said support and along which the said connection 5 is movable during the adjustment of the box, rotation of said cam drawing the said box and support together, and a yielding cushion interposed between the said box and connection to maintain the former in contact with the said 10 support when the said connection is loosened, substantially as described.

3. A bed, a cutter-spindle, adjustable bearing-boxes for the ends of said spindle, a support for said bearing-boxes; connections on 15 and movable with said boxes, independent cam-shaped shafts on which said connections slide during adjustment of the boxes and which act through the medium of said connections to clamp said boxes in adjusted position, and means to operate said cam-shaped shafts simultaneously, whereby either or both ends of said spindle may be shifted into desired adjustment, substantially as described.

4. The combination with a support, of a bearing-box made adjustable thereon, a rotatable cam-rod pivoted at one end to said support and arranged with its axis substantially parallel with the line of box adjustment, a connection on and movable with said 20 box, said connection being provided with an eye at one end to receive said cam-rod for adjustment longitudinally therealong, and having an adjustable head at its other end, and a coiled spring interposed between said 25 box and said adjustable head whereby said spring may be adjusted to render said box connection partially or entirely rigid, as desired, when in clamped position, and yet have a yielding connection for said box when the 30 latter is being adjusted, substantially as described.

5. The combination with a support, and a bearing-box carried by and adjustable along said support, of a cam-rod arranged at that 45 side of said support opposite said bearing-box, and provided with a cam-surface extending from end to end of said cam-rod, and a con-

nnection movable with said box and leading therefrom to the back of said support, and there embracing said cam-rod to be acted 50 upon by the latter at any point in the length thereof to draw said bearing-box against said support in any adjusted position of the said box on said support, substantially as described.

6. The combination with a support, and a bearing-box carried by and adjustable along said support, of a rotatable cam-rod arranged at that side of said support opposite said bearing-box, and provided with a cam-surface 60 extending from end to end of said cam-rod, and a connection movable with said box and leading therefrom to the back of said support, and there embracing said cam-rod to be acted upon by the latter at any point in the length 65 thereof to draw said bearing-box against said support in any adjusted position of the said box on said support, and a spring coöperating with said connection to hold the box against its support during adjustment and while the 70 box is not clamped in its adjustment, substantially as described.

7. The combination with a support, and a bearing-box carried by and adjustable along said support, of a rotatable cam-rod pivoted 75 to said support opposite said box and arranged with its axis substantially parallel with the line of box adjustment, an eyebolt on and movable with said box, said cam-rod being passed through the eye of said bolt, said bolt 80 being provided with a member movable therewith, against which the said cam-rod may bear, as it is rotated, and thereby tighten said bearing-box into clamped position against said support, substantially as described. 85

In testimony whereof we have signed our names to this specification in the presence of two subscribing witnesses.
